ATTORNEY

STATES PATENT OFFICE.

JOHNSON, OF SAN FRANCISCO, CALIFORNIA.

RESILIENT WHEEL.

Specification of Letters Patent. Patented July 25, 1922.

on filed November 12, 1920. Serial No. 423,528.

JOHNSON, a citizen residing at San Francisco, invented certain improvements in a wheel following is

resilient wheels. The invention is interposed between the wheel and the rim may be obviated by pneumatic tires. The invention will appear in the following accompanying drawings.

Fig. 1, side elevation of the invention incorporating a transverse section on a longitudinal

Fig. 2, by numerals, shows an annular inner rim. This rim is provided with a metallic retaining band 5. The band 5 is attached to or formed for forming a pose which will

Fig. 3, band 3 is an annular band which a solid tire. The band 5 is also initially L-shaped and the ears 4 as

Fig. 4, sleeve 9 is a sleeve between the ears 4 in which sleeves are spaced at regular intervals, and is connected by a cable 8 for drawing the sleeves 9 and securing them. The sleeve 9 is a pair of sleeves which are extended between the rims

and which are pivotally connected to the ears 4 and to lugs 13 formed on cleats 14 which are equal in length to the width of the rims. The ends of the cleats 14 are adapted to be engaged by the clips 7 in the manner shown in Figs. 1 and 3 so that the cleats are movable out of engagement with the clips in one direction but are firmly held in engagement with the clips when pulled in the opposite direction. It will be seen that the position of the cable 8 and its manner of connection with the angularly disposed members 12 will give a resiliency to the wheel structure which will obviate the use of pneumatic tires.

What I claim is:—

1. A resilient wheel structure comprising an inner rim provided with a rim band and ears thereon, an outer rim having a rim band provided with clips on its marginal edges, cleats extending transversely and in contact with the said outer rim band and adapted to be engaged by the said clips, the cleats on the outer band being in advance of the ears on the inner band, a cable extending around the space between the bands at the center thereof, and levers arranged in pairs pivotally connected together on the said cable and having their terminals pivotally connected to the said cleats and ears at diagonally opposite points.

2. A resilient wheel structure comprising an inner rim provided with a rim band equipped with ears, an outer rim having a rim band provided with clips on its marginal edges, cleats extending transversely and in contact with the said rim outer band, and adapted to be engaged by the said clips, the cleats on the outer band being in advance of the ears on the inner band, a cable extending around the space between the bands at the center thereof, and levers arranged in pairs pivotally connected together on the said cable and having their terminals pivotally connected to the said cleats and ears at diagonally opposite points, the said cable being equipped with a sleeve at regularly spaced intervals, the said levers being pivotally arranged on the said sleeve and crossing each other at their central points, each

pair of levers being disposed tangentially with respect to the said cable.

3. In a resilient wheel structure, the combination of inner and outer annular bands, an annular cable interposed between and spaced from the said bands, and levers pivotally connected with the inner band and similarly connected with the outer band at

points in advance of the inner connections and receiving the said cable.

In testimony whereof, I have affixed my signature in the presence of two witnesses.

CARL JOHNSON.
